UNITED STATES PATENT OFFICE

HARRY A. HIGGINS, OF DETROIT, MICHIGAN, ASSIGNOR TO LONG MANUFACTURING COMPANY, OF DETROIT, MICHIGAN, A CORPORATION OF MICHIGAN

RADIATOR

Application filed March 23, 1926. Serial No. 96,703.

This invention relates to radiators and more particularly to radiators of the horizontal water tube type in which a tortuous communication between the upper and lower 5 headers is provided.

The invention has as its principal object to improve generally devices of this character by rendering the same more efficient, simple to manufacture and economical to produce. These objects and various other objects, advantages, and novel details of construction of one illustrative embodiment of the invention will be described in detail in the accompanying specification, reference 10 being had to the accompanying drawings wherein;

Figure 1 is a front elevation of a radiator constructed in accordance with this invention;

Figure 2 is an enlarged fragmentary sectional view taken substantially on the plane indicated by line 2—2 in Figure 1;

Figure 3 is a fragmentary sectional view taken substantially on the plane indicated 25 by line 3—3 in Figure 2;

Figure 4 is a fragmentary detail perspective view.

Referring now particularly to the drawings wherein like reference characters indicate like parts, it will be noted that the radiator structure includes upper and lower headers 10 and 11 respectively intermediate which a plurality of horizontally arranged parallel water tubes or compartments are arranged. 30 These sections establish communication between the upper and lower headers and provide tortuous passages through which the water travels or in a manner to be more fully hereinafter referred to.

Each of the water tubes or compartments 40 12 comprises a pair of spaced walls 13 peripherally united as at 14. Each section 12 may either be formed of a single sheet of metal bent longitudinally thereof with the free longitudinal edges united as shown at 15 in Figure 4, or each section may be composed of two separate sheets suitably peripherally united as is well known in this art. The edges 45 of the walls 13 are united at the ends as indicated at 16 so that each section 12 constitutes

a separate water compartment or chamber.

In constructing a radiator, a plurality of the sections 12 are arranged in superposed relation with the sections extending horizontally and with their longitudinal edges exposed at the front and rear of the radiator. 55

The sections 12 in the assembled radiator are spaced apart by outwardly projecting protuberances formed in the walls to provide air spaces therebetween which extend from the front to the rear of the radiator as will be readily apparent. The aforesaid protuberances consequently project into this air space and as the water to be cooled is flowing through these protuberances the radiating 60 surface of the radiator is increased and its heat dissipating efficiency enhanced. 65

For providing communication between adjacent sections of the radiator to thus provide for communication between the headers 10 and 11 the walls of each section are provided with the aforesaid outwardly directed protuberances indicated at 17. These protuberances may be of the shape or contour illustrated in the drawings wherein the circular 70 pan-shape portion 18 of each protuberance terminates in a vertical projection or nipple portion 19 of relatively smaller diameter. The ends of each protuberance is perforated 75 or provided with an opening 20. 80

The protuberances 17 may as illustrated in the drawings, be arranged in rows transversely of each section but it is preferable that the rows of protuberances formed in the opposed walls of each section be disaligned 85 vertically. However a uniformity of spacing of the rows of protuberances is maintained in each of the sections 12 so that when superposed in the manner illustrated the rows of protuberances formed in the lower wall of one section 12 will coincide with the rows of protuberances formed in the upper wall of the next lower section. Thus, the ends of adjacent protuberances are arranged in abutting relation and a water tight union may be effected therebetween in any well known manner, such for instance as soldering the joints. By reason of the openings 20 in the protuberances the interior of adjacent sections 12 are made intercommunicating. However, it 90 95 100

will be noted that owing to the disalignment of the rows of protuberances of each section 12 tortuous or angular passages are provided through which the water traveling from the upper to the lower header must take.

5 Obviously the protuberances formed in the upper wall of the uppermost section 12 and the protuberances formed in the lower wall of the lowermost section will communicate directly with the upper and lower headers 10 and 11 respectively.

15 Therefore, in operation water flowing through the radiator will enter one of the sections 12 through the rows of protuberances formed for instance in the upper wall thereof whereupon it will spread out in a thin sheet between the upper and lower walls of this section in order to continue its downward flow through the next adjacent rows of 20 protuberances which are out of vertical alignment with the rows of protuberances in the upper wall. This zigzag or tortuous passage of the water will be maintained throughout its entire flow through the radiator and an 25 intimate contact between the water and the walls of the radiator sections will be assured. Consequently an efficiency of heat dissipation is obtained resulting in a thorough cooling of the water or other liquid.

30 The construction of the radiator sections as well as the assembling of the same in constructing the radiator is rendered simple and economical by reason of the character of the herein described design and in addition an 35 efficient radiation is obtained.

While an embodiment of the invention has been described and illustrated somewhat in detail various changes in these details may be resorted to without departing from the spirit 40 and scope of the invention and to this end reservation is made to make such changes as may come with the purview of the accompanying claims.

What I claim as my invention is:

45 1. In a radiator, a plurality of sections each comprising a hollow member constituting a water chamber and extending horizontally of the radiator, and means for establishing communications between said sections, said 50 means including a plurality of identically shaped protuberances formed on each section, each of said protuberances including a relatively wide tubular base portion and a reduced tubular end portion, the reduced tubular 55 end portion of each protuberance being adapted for abutting engagement with the reduced tubular end portion of the corresponding protuberance of the next adjacent section.

60 2. In a radiator, a plurality of sections each comprising a hollow member constituting a water chamber and extending horizontally of the radiator, and means for establishing communication between said sections, said 65 means including a plurality of outwardly

directed disaligned perforated protuberances formed on each section, each of the said protuberances including a relatively wide tubular base portion and a reduced tubular end portion, the free edge of the wall defining the reduced tubular end portion of each protuberance being adapted for abutting engagement with the free edge of the wall defining the reduced tubular end portion of the corresponding protuberance of the next adjacent section.

In testimony whereof I affix my signature.
HARRY A. HIGGINS.
